UNITED STATES PATENT OFFICE.

WILLIAM J. McMARLIN, OF PITTSBURGH, PENNSYLVANIA, AND LAWRENCE H. STRAYER, OF KENT, OHIO, ASSIGNEES TO McDOWELL MANUFACTURING COMPANY, OF PITTSBURGH, PENNSYLVANIA, A CORPORATION OF PENNSYLVANIA.

DESIGN FOR A TOY POPGUN.

Application filed September 13, 1927. Serial No. 23,402. Term of patent 7 years.

To all whom it may concern:

Be it known that we, WILLIAM J. McMARLIN and LAWRENCE H. STRAYER, both citizens of the United States, residing, respectively, at Pittsburgh, county of Allegheny, and State of Pennsylvania, and Kent, county of Portage, and State of Ohio, have invented a new, original, and ornamental Design for Toy Popguns, of which the following is a specification, reference being had to the accompanying drawing, forming part thereof.

The figure shown in the drawing is a perspective view of a toy pop gun embodying the invention.

We claim:

The ornamental design for a toy popgun, as shown.

In testimony whereof we have hereunto set our hands.

WILLIAM J. McMARLIN.
LAWRENCE H. STRAYER.
